DESIGN FOR A SURVEYOR'S ROD

John W. Malot, Hustontown, Pa.

Application July 27, 1945, Serial No. 121,020

Term of patent 14 years

(Cl. D52—1)

To all whom it may concern:

Be it known that I, John W. Malot, a citizen of the United States, residing at Hustontown, in the county of Fulton and State of Pennsylvania, have invented a new, original, and ornamental Design for a Surveyor's Rod, of which the following is a specification, reference being had to the accompanying drawing, forming a part thereof.

The figure is a perspective view of a surveyor's rod, showing my new design.

I claim:

The ornamental design for a surveyor's rod, as shown.

JOHN W. MALOT.
